UNITED STATES PATENT OFFICE.

JOSEPH BRAUNINGER, OF TRENTON, NEW JERSEY.

GAS-STOVE.

1,150,384.

Specification of Letters Patent. Patented Aug. 17, 1915.

Application filed March 5, 1915. Serial No. 12,460.

To all whom it may concern:

Be it known that I, JOSEPH BRAUNINGER, a citizen of the United States, residing at Trenton, in the county of Mercer and State of New Jersey, have invented a certain new and useful Gas-Stove, of which the following is a specification.

This invention relates to gas stoves and has special reference to a combined gas stove and water heater forming an improvement over my prior application for patent on combined gas stoves and water heaters, filed March 9, 1914, and bearing the Serial Number 823,484.

15 I have found, in using the stove of my prior application, that the lateral gas supply pipes could be dispensed with by modifying the structure in certain ways, and this without affecting its efficiency as either a stove or water heater.

20 One object of the invention, therefore, is to produce a modified and improved stove of the general type previously disclosed in my prior application and which will enable 25 the lateral gas supply pipes to be dispensed with without in any way affecting the efficiency of the device.

25 I have also found, in practice, that it is advisable, both for improving the manner 30 of heating the water and for increasing the life of the device, that the lateral flame passages be water jacketed.

35 A second object of the invention is, therefore, to provide an improved stove of this 40 class having a water space arranged to jacket all the flame passages.

A third object of the invention is to improve the burner structure in a device of this character.

45 With the above and other objects in view as will be hereinafter apparent the invention consists in general of certain novel details of construction and combinations of parts hereinafter fully described, illustrated 50 in the accompanying drawings, and specifically claimed.

In the accompanying drawings, like characters of reference indicate like parts in the several views, and Figure 1 is a plan view 55 of the improved stove. Fig. 2 is a section on the line 2—2 of Fig. 1. Fig. 3 is an enlarged detail section on the line 3—3 of Fig. 1. Fig. 4 is a detail plan view partly in section with the hood removed. Fig. 5 is 60 an end view of the device showing a modi-

fied form of hood in section. Fig. 6 is a detail end view of the burner tube.

In carrying out the above mentioned objects there is provided an inner casing which contains the combustion chamber 10 and the 60 water heating chamber indicated in general at 11.

This water heating chamber consists of a main body portion 12 surrounding the combustion chamber of substantially inverted 65 U-shape and a peripheral or flange portion 13 extending laterally from the upper part of the main water heating chamber. Depending from the outer edges of the flange portion are skirt walls 14. Extending laterally through the legs of the main body portion is a plurality of tubular flame passages 15 and through the flange portion extend similar flame passages 16 extending vertically through such flange portion. 70

In the main water heating chamber there is a water inlet opening 17, an outlet opening 18 and a cleanout opening 19. Furthermore there is a central vertical opening 20 extending through the bight of the U-shaped 80 body portion of the water heating chamber. It will thus be evident that all of the flame passages are water jacketed. 75

Extending through the chamber 10 is a burner or mixing tube 21 the body portion 85 of which is oblatelately ovate in cross section and which is provided with lateral openings 22 for the escape of mixed gas and air, the gas being admitted through a tube 23 and the air being admitted through an opening 90 24 controlled by a rotary valve 25. This tube 22 is provided adjacent the inlet end with a Venturi-tube portion 26 for the purpose of better mixing the air and gas and of producing a more even and uniform flow. 95

In both the forms shown in Figs. 1 and 2 and the form shown in Fig. 5 there is provided a hood 27 but in the first form, which is designed to use the device as a stove as well as a water heater, a spreader cone 28 100 is provided above the opening 20 and this spreader cone is surrounded by openings 29 for the escape of the heated air and products of combustion from the openings 20.

In each case the hood is held spaced from 105 the heater by suitable means such as is shown at 30.

The device, when in use, heats the water in the water chamber in a highly efficient manner owing to the fact that the flame 110

passages 15, 16 and 20 are all completely surrounded by water.

Having thus described my invention, what is claimed as new, is:

- 5 1. In a stove of the class described, an inner casing having a water chamber disposed therein and provided with lateral flange portions extending from and communicating with its upper part, said casing having 10 a horizontally extending tubular opening formed substantially central thereof and being provided with skirt walls depending from the outer edges of the horizontal portions of the water chamber to form lateral 15 pockets at the sides of the tubular opening, there being walled openings through the sides of the water chamber affording communication between the central opening and the pockets and the horizontal portions of 20 the water chamber over the pockets being provided with vertically disposed walled openings.
2. In a stove of the class described, an inner casing having a water chamber disposed 25 therein and provided with lateral flange portions extending from and communicating with its upper part, said casing having a horizontally extending tubular opening formed substantially central thereof and being provided with skirt walls depending from the outer edges of the horizontal portions of the water chamber to form lateral 30 pockets at the sides of the tubular opening, there being walled openings through the sides of the water chamber affording communication between the central opening and the pockets and the horizontal portions of the water chamber over the pockets being provided with vertically disposed walled 35 openings, there being a further walled opening extending through the water chamber above the central opening.
3. In a stove of the class described, an inner casing having a water chamber disposed 40 therein and provided with lateral flange portions extending from and communicating with its upper part, said casing

having a horizontally extending tubular opening formed substantially central thereof and being provided with skirt walls depending from the outer edges of the horizontal portions of the water chamber to form lateral pockets at the sides of the tubular opening, there being walled openings through the sides of the water chamber affording communication between the central opening and the pockets and the horizontal portions of the water chamber over the pockets being provided with vertically disposed walled openings, there being a further walled opening extending through the water chamber above the central opening; in combination with a hood extending over the stove and having an annular series of openings surrounding the last mentioned opening in the stove, and a spreader cone on the hood concentric with said last mentioned opening and the series of hood openings.

4. In a stove of the class described, an inner casing having a water chamber disposed therein and provided with lateral flange portions extending from and communicating with its upper part, said casing having a horizontally extending tubular opening formed therethrough and being provided with skirt walls depending from the outer edges of the lateral portions of the water chamber to form lateral pockets at the sides of the tubular opening, there being walled openings through the sides of the water chamber affording communication between the tubular opening and the pockets, the horizontal portions of the water chamber over the pockets being provided with vertically disposed walled openings, and a hood covering the water chamber.

In testimony whereof, I affix my signature, in the presence of two witnesses.

JOSEPH BRAUNINGER.
